SHAVING DEVICE

Stanley Strzelecki, Brooklyn, N. Y.

Application November 27, 1937, Serial No. 176,775

8 Claims. (Cl. 30—43)

This invention relates generally to shaving devices for cutting whiskers or other hair from the skin without the use of any applicator to the skin, but more specifically to a cutting head for such a device which has a double row of cutting teeth operating successively during passage of the cutting head over the skin.

The main object of the invention resides in the provision of a cutting head having a central and longitudinal opening whereby the operative surface of the cutting head affords two spaced rows of cutting teeth operating simultaneously and adapted to pass over the same skin areas during movement of the cutting head.

Another object of the invention resides in the provision of a cutting head having an operative surface which is adapted to be placed on the skin and wherein the handle therefor is disposed in a plane substantially parallel to the said operative surface.

A further object of the invention resides in the provision of a cutting head which is economical to manufacture, simple to operate and highly efficient in operation.

These objects and other incidental ends and advantages will hereinafter appear in the progress of the disclosure and as pointed out in the appended claims.

Accompanying this specification is a drawing showing a preferred embodiment of the invention wherein corresponding reference characters designate corresponding parts throughout the several views and wherein:

Figure 1 is a side view of an assembled razor with handle embodying my invention.

Figure 2 is an end elevation of the upper portion of Figure 1.

Figure 3 is an enlarged view of the cutting head portion of the razor shown in Figure 1.

Figure 4 is a sectional view of Figure 3 through the plane 4—4 thereof.

Figure 5 is a top plan view of the stationary cutter member of the cutting head.

Figure 6 is a sectional view of Figure 5 through the plane 6—6 thereof.

Figure 7 is a top plan view of the movable cutter of the cutting head.

Figure 8 is a sectional view of Figure 7 through the plane 8—8 thereof.

Figure 9 is a detail perspective side view of the handle or carrier to which the cutting head is attached and illustrating the actuating member for the movable cutter.

In accordance with the invention and in accordance with the preferred form thereof shown

in the drawing, numeral 10 indicates a handle of any suitable design and shape and is provided with a forward extension 11 at the top thereof. Extension 11 is provided with a channel 12 at the end wall thereof, the said channel being adapted to receive the cutting head comprising a stationary cutter member 13 and a movable cutter member 14. The handle 10 is adapted to enclose an electric motor or other power device adapted to oscillate longitudinally of channel 12 an actuating arm 15 having a bend 16 terminating into channel 12 for operative engagement with the movable cutter member 14.

The stationary cutter member is preferably comprised of a section of steel tubing which is usually made of sheet metal and each of whose sides is uniform in thickness and as shown is square in shape, the side containing spaced teeth 17, which latter extend downwardly along the side walls, being provided with an opening 18 disposed longitudinally of the cutter member and intermediate the width of the side mentioned. Cutter member 13 is provided with a central orifice 19 on the wall opposite to the toothed wall and is of a size sufficient to receive the end 20 of the actuating arm 15 and permit oscillation thereof within the said orifice. The stationary cutter member 13 is also provided with orifices 20' and 21 adjacent to and on the same wall as orifice 19, the said orifices 20' and 21 engaging securing lugs 22 and 23 situated on the rear upright wall of channel 12. The rear upright wall of channel 12 is also provided with a central opening 24 to permit insertion therethrough of portion 16 of actuating arm 15. When the stationary cutter member 13 is inserted in channel 12, orifices 19 and 24 are in alignment while orifices 20' and 21 engage lugs 22 and 23 respectively thereby securing the cutter in the channel. A set screw 25 is also provided which penetrates the upper wall of channel 12 and impinges against the top wall of cutter 13 as best shown in Figure 4.

The movable cutter 14 is comprised of a section of steel tubing similar in shape to the stationary cutter 13 and is reduced in dimensions to reciprocate within the latter. The cutter 14 is provided with a central and longitudinal opening 26 intermediate the width of the wall or side containing teeth 27, the opening 26 being adjacent to the opening 18 of the stationary cutter when the cutters are assembled for operation. A central orifice 28 is provided on the opposite wall of cutter 14 and is adapted to engage end 20 of actuating arm 15.

The assembly and operation of the aforementioned shaving device is indeed very simple.

Moreover, the manufacture of the cutting head consisting of the stationary cutter member 13 and the movable cutter member 14 is accomplished very easily and economically by applying a series of spaced grooving cutters to the operative walls of the tubular cutter members thereby resulting in the formation of two rows of cutting teeth oppositely disposed of the longitudinal openings.

In order to assemble the cutting head in channel 12 for operation, the movable cutter 14 is fitted within the stationary cutter 13 so that orifices 28 and 19 are in alignment. In such position, the two cutters are inserted into channel 12 of handle 10 so that end 20 of actuating arm 16 penetrates both orifices. Lugs 22 and 23 are made to engage orifices 20' and 21 situated 20 in the rear wall of stationary cutter 13. The faces of lugs 22 and 23 form a continuous surface with the rear wall of stationary cutter 13, thereby permitting reciprocal motion of the movable cutter 14 within the stationary cutter 13. A set 25 screw 25, having first been elevated from channel 12 to permit insertion of the cutting head, is now tightened to impinge against the top wall of the stationary cutter 13, thereby securing the latter fixedly in place.

30 In operation, the stationary cutter is pressed against the skin, so that the teeth lying in the plane parallel to the rear wall of the cutter containing orifices 19, 20 and 21, lie against and coplanar with the skin. When the cutting head 35 13, is passed over the skin, the hairs are combed into the grooves between the teeth 17 by virtue of the outer corners of the teeth formed by the intersection of the side containing the spaced teeth 17 and the adjacent side walls. Since the 40 movable cutter 14, which is similar in construction to cutter 13 except that there are less teeth and wider resultant grooves, oscillates rapidly within the stationary cutter, at any given instant a number of grooves in 14 coincide with the grooves in 45 stationary cutter 13. In this position the hairs, which pass thru the grooves in the stationary cutter 13, pass on into the coinciding grooves in movable cutter 14. When movable cutter 14 continues its movement in a plane at right angles 50 to the axis of the hairs, the grooves in 14 move away from the coinciding grooves in 13 and thus shear the hairs off between the upper surface of teeth 27 and the undersurface of teeth 17. The depth between the wall containing spaced 55 teeth 17 of the stationary cutter and the rear wall of the movable cutter determines the length of hair that can be cut by the cutting head. Moreover, the thickness of the wall of the stationary cutter containing teeth 17 determines 60 the depth of cut for each hair.

The purpose of the aligned openings is to divide the cutting members into two parts, so as to have two rows of cutting teeth, one following closely behind the other, allowing for a shave 65 and 1 shave in one operation.

I wish it understood that minor changes and variations in the position, integration, material, conformation and combination and subcombination of parts may all be resorted to without departing from the spirit of the invention and without departing from the scope of the appended 70 claims.

I claim:

1. In a shaving device, a tubular stationary 75 cutter formed of sheet metal and having a flat op-

erative wall provided with a longitudinal slot intermediate the width thereof, side and rear walls each of uniform thickness, the flat operative wall being provided with a series of spaced and transverse slits running across the said operative wall and extending downwardly into the side walls to form teeth between the said slits, the said teeth having free opposed ends along the longitudinal slot and combing corners at the line of meeting between the operative and side walls, a movable and tubular cutter member similarly formed of sheet metal reciprocably mounted within the stationary cutter member and similarly provided with a flat operative wall having a longitudinal slot intermediate the width thereof, side and rear walls each of uniform thickness, the flat operative wall being provided with a series of transverse slits running across the said operative wall and extending downwardly into the side walls to form teeth between the said slits, the slits of the movable cutter being spaced farther apart than the slits of the stationary cutter member, the teeth of the movable cutter having free opposed ends along the longitudinal slot and combing corners at the line of meeting between the operative and side walls, the slots of both the stationary and movable cutters being in alignment and being adapted to afford a double row of cutting teeth, a handle member to the plane of which the stationary and movable cutter members are mounted at right angles.

2. In a shaving device, a tubular stationary cutter member formed of sheet metal and being rectangular in cross section and having a forward wall provided with a longitudinal slot intermediate the width thereof, side and rear walls each of uniform thickness, the forward wall being provided with a series of spaced and transverse slits running across the said forward wall and extending downwardly into the side walls to form teeth between the said slits, the said teeth having free opposed ends along the longitudinal slot and combing corners at the line of meeting between the forward and side walls, a movable and tubular cutter member similarly formed of sheet metal and being rectangular in cross section and being reciprocably mounted within the stationary cutter member and similarly provided with a forward wall having a longitudinal slot intermediate the width thereof, side and rear walls each of uniform thickness, the forward wall being provided with a series of parallel and spaced transverse slits running across the said forward wall and extending downwardly into the side walls to form teeth between the said slits, the teeth of the movable cutter similarly having free opposed ends along the longitudinal slot and combing corners at the line of meeting between the forward and side walls, the slots of both the stationary and movable cutters being in alignment and being adapted to afford a double row of cutting teeth, a handle member to the plane of which the stationary and movable cutter members are mounted at right angles.

3. In a shaving device, a tubular stationary cutter formed of sheet metal and having a flat operative wall provided with a longitudinal slot intermediate the width thereof, side and rear walls each of uniform thickness, the flat operative wall being provided with a series of spaced and transverse slits running across the said operative wall and extending downwardly into the side walls to form teeth between the said slits, the said teeth having free opposed ends along the longitudinal slot and combing corners at the line of meeting 75

5 between the operative and side walls, a movable and tubular cutter member similarly formed of sheet metal reciprocably mounted within the stationary cutter member and similarly provided with a flat operative wall having a longitudinal slot intermediate the width thereof, side and rear walls each of uniform thickness, the flat operative wall being provided with a series of spaced and transverse slits running across the said operative wall and extending downwardly into the side walls to form teeth between the said slits, the teeth of the movable cutter having free opposed ends along the longitudinal slot and combing corners at the line of meeting between the operative and side walls, the slots of both the stationary and movable cutters being in alignment and being adapted to afford a double row of cutting teeth.

10 6. In a shaving device, a tubular stationary cutter member formed of sheet metal and being rectangular in cross section and having a forward wall provided with a longitudinal slot intermediate the width thereof, side and rear walls each of uniform thickness, the forward wall being provided with a series of spaced and transverse slits running across the said forward wall and extending downwardly into the side walls to form teeth between the said slits, the said teeth having free opposed ends along the longitudinal slot and combing corners at the line of meeting between the forward and side walls, a movable and tubular cutter member similarly formed of

15

20

20 mounted at right angles.

4. In a shaving device, a tubular stationary cutter having a flat operative wall provided with a longitudinal slot intermediate the width thereof, side and rear walls each of uniform thickness, 25 the flat operative wall being provided with a series of spaced and transverse slits running across the said operative wall and extending downwardly into the side walls to form teeth between the said slits, the said teeth having free opposed ends 30 along the longitudinal slot and combing corners at the line of meeting between the operative and side walls, a movable and tubular cutter member reciprocably mounted within the stationary cutter member and similarly provided with a flat 35 operative wall having a longitudinal slot intermediate the width thereof, side and rear walls each of uniform thickness, the flat operative wall being provided with a series of spaced and transverse slits running across the said operative wall 40 and extending downwardly into the side walls to form teeth between the said slits, the teeth of the movable cutter having free opposed ends along the longitudinal slot and combing corners at the line of meeting between the operative and side 45 walls, the slots of both the stationary and movable cutters being in alignment and being adapted to afford a double row of cutting teeth, a handle member to the plane of which the stationary and 50 movable cutter members are mounted at right angles.

20 mounted at right angles.

4. In a shaving device, a tubular stationary cutter formed of sheet metal and being rectangular in cross section and being reciprocably mounted within the stationary cutter member and similarly provided with a forward wall having a longitudinal slot intermediate the width thereof, side and rear 25 walls each of uniform thickness, the forward wall being provided with a series of parallel and spaced transverse slits running across the said forward wall and extending downwardly into the side walls to form teeth between the said slits, the teeth of the movable cutter similarly having free opposed ends along the longitudinal slots and combing corners at the line of meeting between the forward and side walls, the slots of both the stationary and movable cutters being in 30 alignment and being adapted to afford a double row of cutting teeth.

7. In a shaving device, a tubular stationary cutter formed of sheet metal and having a flat operative wall provided with a longitudinal slot 35 intermediate the width thereof, side and rear walls each of uniform thickness, the flat operative wall being provided with a series of spaced and transverse slits running across the said operative wall and extending downwardly into the side walls to form teeth between the said slits, the said teeth having free opposed ends along the longitudinal slot and combing corners at the line of meeting between the operative and side 40 walls, a movable and tubular cutter member similarly provided with a forward wall having a longitudinal slot intermediate the width thereof, side and rear walls each of uniform thickness, the forward wall being provided with a series of parallel and spaced transverse slits running across the said forward wall and extending downwardly into the side walls to form teeth between the said slits, the teeth of the movable cutter similarly having free opposed ends along the longitudinal slots and combing corners at the line of meeting between the forward and side walls, the slots of both the stationary and movable cutters being in 45 alignment and being adapted to afford a double row of cutting teeth.

7. In a shaving device, a tubular stationary cutter formed of sheet metal and having a flat operative wall provided with a longitudinal slot 50 intermediate the width thereof, side and rear walls each of uniform thickness, the flat operative wall being provided with a series of spaced and transverse slits running across the said operative wall and extending downwardly into the side walls to form teeth between the said slits, the said teeth having free opposed ends along the longitudinal slot and combing corners at the line of meeting between the operative and side walls, a movable and tubular cutter member similarly provided with a forward wall having a longitudinal slot intermediate the width thereof, side and rear 55 walls each of uniform thickness, the forward wall being provided with a series of parallel and spaced transverse slits running across the said forward wall and extending downwardly into the side walls to form teeth between the said slits, the teeth of the movable cutter similarly having free opposed ends along the longitudinal slots and combing corners at the line of meeting between the forward and side walls, the slots of both the stationary and movable cutters being in alignment and being adapted to afford a double row of cutting teeth.

5. In a shaving device, a tubular stationary cutter formed of sheet metal and having a flat operative wall provided with a longitudinal slot intermediate the width thereof, side and rear walls each of uniform thickness, the flat operative wall being provided with a series of spaced and transverse slits running across the said operative wall and extending downwardly into the side walls to form teeth between the said slits, the said teeth having free opposed ends along the longitudinal slot and combing corners at the line of meeting between the operative and side walls, a movable and tubular cutter member similarly formed of sheet metal reciprocably mounted with 60 in the stationary cutter member and similarly provided with a flat operative wall having a longitudinal slot intermediate the width thereof, side and rear walls each of uniform thickness, the flat operative wall being provided with a series of transverse slits running across the said operative wall and extending downwardly into the side walls to form teeth between the said slits, the slits of the movable cutter being spaced 65 farther apart than the slits of the stationary cutter member, the teeth of the movable cutter hav- 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470

similarly formed of sheet metal reciprocably mounted within the stationary cutter member and similarly provided with a flat operative wall having a longitudinal slot intermediate the width thereof, side and rear walls each of uniform thickness, 55 the flat operative wall being provided with a series of spaced and transverse slits running across the said operative wall and extending downwardly into the side walls to form teeth between the said slits, the teeth of the movable cutter having 60 free opposed ends along the longitudinal slot and combing corners at the line of meeting between the operative and side walls, the slots of both the stationary and movable cutters being in alignment and being adapted to afford a double 65 row of cutting teeth.

8. In a shaving device, a tubular stationary cutter having a flat operative wall provided with a longitudinal slot intermediate the width thereof, side and rear walls each of uniform thickness, 70 the flat operative wall being provided with a series of spaced and transverse slits running across the said operative wall and extending downwardly into the side walls to form teeth between the said slits, the said teeth having free opposed ends 75

along the longitudinal slot and combing corners at the line of meeting between the operative and side walls, a movable and tubular cutter member reciprocably mounted within the stationary cutter member and similarly provided with a flat operative wall having a longitudinal slot intermediate the width thereof, side and rear walls each of uniform thickness, the flat operative wall being provided with a series of spaced and transverse slits running across the said operative wall and

extending downwardly into the side walls to form teeth between the said slits, the teeth of the movable cutter having free opposed ends along the longitudinal slots and combing corners at the line of meeting between the operative and side walls, the slots of both the stationary and movable cutters being in alignment and being adapted to afford a double row of cutting teeth. 5

STANLEY STRZELECKI. 10
